DESIGN FOR A WHATNOT OR SIMILAR ARTICLE

Edward C. Herron, East St. Louis, Ill.

Application February 11, 1938, Serial No. 75,060

Term of patent 7 years

To whom it may concern:

Be it known that I, Edward C. Herron, a citizen of the United States, residing in the city of East St. Louis, county of St. Clair, and State of Illinois, have invented a new, original, and ornamental Design for Whatnots or Similar Articles, of which the following is a specification, reference being had to the accompanying drawing, forming a part thereof.

In the drawing: Fig. 1 is a top plan view of a whatnot, showing my new design; Fig. 2 is a front elevational view of the whatnot, and Fig. 3 is a side elevational view of the article shown by Figs. 1 and 2.

I claim:

The ornamental design for a whatnot or similar article, substantially as shown.

EDWARD C. HERRON.
